UNITED STATES PATENT OFFICE.

WILLIAM B. HODGE, OF CHARLOTTE, NORTH CAROLINA, ASSIGNOR, BY MESNE ASSIGNMENTS, TO PARKS-CRAMER COMPANY, OF FITCHBURG, MASSACHUSETTS, A CORPORATION OF MASSACHUSETTS.

SYSTEM OF DISTRIBUTION FOR HUMIDIFYING, HEATING, AND AIR-CONDITIONING APPARATUS.

1.284.336.

Specification of Letters Patent. Patented Nov. 12, 1918.

Original application filed May 6, 1913, Serial No. 765,749. Divided and this application filed June 21, 1915.
Serial No. 35,394.

To all whom it may concern:

Be it known that I, WILLIAM B. HODGE, a citizen of the United States, residing at Charlotte, in the county of Mecklenburg and 5 State of North Carolina, have invented certain new and useful Improvements in Systems of Distribution for Humidifying, Heating, and Air-Conditioning Apparatus; and I do hereby declare the following to be a full, 10 clear, and exact description of the invention, such as will enable others skilled in the art to which it appertains to make and use the same.

15 This application is a division of application Serial No. 765,749, filed May 6th, 1913, and has for its object the purpose of more thoroughly and uniformly moistening hygroscopic materials than has been possible heretofore.

20 In the accompanying drawings, which form part of this specification:—

Figure 1 represents a sectional perspective elevation of an ordinary room with a loom, such as is used in weaving cloth.

25 Fig. 2 represents a sectional elevation of the end of the room and the floor of the mill showing a distributing pipe.

Fig. 3 represents a sectional end elevation of Fig. 2 on line 3—3.

30 Fig. 4 represents a plan view of the distributor.

Reference being had to the drawings and the designating characters thereon, I indicates a duct of galvanized iron or other suitable material for conveying air from a fan or other suitable source of supply (not shown), but heated and moistened to any desired degree. This main duct may extend across the mill, and thence by lateral ducts 1' along or through the mill, directly underneath the line of looms or other machinery on which is placed the hygroscopic material that it is desired to humidify.

3 indicates a temperature and humidity controller through which the air from duct 1 is forced and passed over thermo-responsive members, and by means of which both the temperature and the humidity of the air entering the duct 1 is controlled to any desired degree. Such a humidity controller is illustrated and described in U. S. Patent 1,075,197 granted October 7, 1913, Patent

No. 856,944 of June 11, 1907, and, consequently does not need further description.

6 indicates a loom, the warp threads of which it is desired to keep moistened so as to prevent breakage of the warp and produce better, and smoother work. 55

7 indicates the beam on which the warp threads are wound. 60

8 indicates the outlet from duct 1', by means of which the humidified and conditioned air from the duct 1 is let up through the pipe 9 and discharged against the beam 7.

It is well known that hygrostatic substances hold an amount of moisture substantially dependent upon the humidity and temperature of the air which surrounds them. For instance, in the case of cotton, if the 70 temperature and humidity of a room in which cotton is placed, is accurately known, the moisture content of the cotton stored in that room can be ascertained from a tabulated chart quite as accurately as by drying 75 the cotton out and estimating the percentage of moisture by mathematical calculation. The same applies to other fibers, such as silk and wool, and to hygroscopic materials such as grain, tobacco and the like. In fact, it appears to be a physical law that any hygroscopic material standing in a room with certain 80 conditions of temperature and humidity, absorbs or gives off more or less moisture until its moisture content is exactly what the temperature and humidity conditions of the room indicate for that particular 85 substance. Consequently, by directing against hygroscopic material, such as cotton, tobacco and the like, an air blast of certain 90 predetermined temperature and humidity, we can impart to said hygroscopic material the desired moisture content that corresponds to the temperature of the air employed. 95

In this particular case by directing a blast of air as shown in Fig. 2, directly against the warp on a loom, we can maintain those warp threads at any desired moisture content, depending upon the humidity and temperature setting of the regulator 3, and similarly, by somewhat changing the shape of the outlet of diffuser 8, we can attach above it either skeins or cones of cotton or various

manufactured products in other forms, by means of which the air issuing from the diffuser 8 would encompass and penetrate whatever hygroscopic substance was being 5 treated, and it would attain the moisture content indicated by the temperature and humidity of the air issuing against it.

Such a device as this is extremely important as it enables such hygroscopic materials to be conditioned to a much higher moisture content than could be continually 10 withstood at times by operatives in the room. And, furthermore, it allows a distinctly local conditioning process and can be carried 15 on in a much simpler, more economical and quicker manner by using the blast of air or by merely allowing these substances to stand quiet in a dead atmosphere.

The practical operation of this apparatus, 20 merely depends upon setting regulator 3 so that the temperature and humidity of the air carried through the duct 1 and discharged through diffuser 8 shall be of the required character to produce the desired 25 moisture content in whatever hygroscopic material is used above the diffuser. It is, of course, evident that the diffuser should be made of the proper shape to get a uniform 30 distribution or volume of air along its entire length, which, of course, in the case of moistening a beam on the loom would be extended as shown on the drawing. In moistening cotton in the form of cones, skeins or other well known forms, a some-

what different shape of outlet would be 35 necessary, depending upon the exact shape of the product to be conditioned, and in handling tobacco, grain and other hygroscopic materials, even still different shaped outlets would be desirable. 40

Furthermore, it is evident that in such distribution it would not be necessary, although it is convenient, to have the distributing pipe underneath the floor, inasmuch as any arrangement for distributing 45 a properly conditioned current of air against the hygroscopic material under treatment will fall within the scope of this invention.

Having thus fully described my invention, 50 what I claim is:—

In an apparatus for supplying conditioned air to hygroscopic material undergoing treatment, the combination with a conduit having a nozzle arranged to direct the air upon such material, a temperature and humidity controller arranged in said conduit and operating upon the condition of such air or any change therein to control and regulate the temperature and humidity of the air to the optimum condition of such 55 hygroscopic material.

In testimony whereof I affix my signature in presence of two witnesses.

WILLIAM B. HODGE.
